UNITED STATES PATENT OFFICE.

RALPH A. SCHOENBERG, OF BRANCHPORT, NEW JERSEY, ASSIGNOR TO IDA S.
ROSENHEIM, OF NEW YORK, N. Y.

MEANS FOR OPERATING SWITCH MECHANISMS.

1,149,789.

Specification of Letters Patent. Patented Aug. 10, 1915.

Application filed February 9, 1914. Serial No. 817,472.

To all whom it may concern:

Be it known that I, RALPH A. SCHOENBERG, of Branchport, in the county of Monmouth and State of New Jersey, have invented new and useful Means for Operating Switch Mechanisms, of which the following is a specification.

My invention relates to means for operating switch mechanisms and particularly when such mechanisms are placed in sockets or other receptacles especially when adapted for carrying electric light lamps or attachment plugs.

In the case of sockets or other receptacles it is highly desirable to do away with the unsightliness caused by protruding actuators, such as keys, chains and push-buttons. These actuators are a distinct drawback as a matter of appearance and particularly in the case of very fine fixtures and require not only perforation of the socket or other receptacle but also perforation of the husk or socket cover when the latter is used as well as alinement of the perforations of socket and husk. Although this has been recognized the attempt to do away with this feature has heretofore usually necessitated a distinct wall switch for each fixture but it has been suggested to use a rotary lamp. A rotary lamp, however, has many objections and the main object of my invention is to do away with such protruding actuators and also to eliminate the rotation of the supporting member for the lamp, attachment plug or other device.

My invention consists mainly in providing means at the end of the receptacle moving longitudinally to actuate the switch mechanism and this longitudinal movement is in a direction substantially parallel to the wall of the socket or other receptacle no matter in what direction the lamp or other device may point, that is, whether it is vertical or horizontal or at an angle with the horizontal.

A feature of my invention consists in providing a quick make and quick break bridging member moving longitudinally.

Another feature of my invention is that in the case of lamps I avoid the necessity of a protracted grasp of the lamp with the consequent likelihood of burning the hand as is the case with a rotary lamp for operating the switch.

Another feature of my invention is that I

avoid all arcing which will be present in the case of a rotary lamp when the latter is turned in the reverse direction, this likelihood of arcing being present especially in high wattage lamps.

Another feature is that an attachment plug can be placed in the socket and operated by a pull on a cord attached to the plug where the plug is not within reach or where a quick method of breaking the current is desired.

A further advantage is that there is no likelihood of breaking the lamp as might be the case if a rotary lamp were used for the reason that there are now many standard keyless sockets now in use and the operator would try to rotate the lamp not knowing whether the device were operable by rotation of the lamp or not and if it were not the lamp would undoubtedly break in the hand of the user.

A further feature of my invention is that in case the lamp or other device is out of convenient reach a chain or other member attached to the supporting member may be used to move the supporting member and this could not be done with a rotary lamp.

In one embodiment of my invention which I disclose herein, this being for some purposes the preferred form, I provide a socket which carries switch mechanism and movably mounted on the socket is a lamp support carrying a lamp, longitudinal movement of the lamp support acting to make and break a circuit through the switch to light the lamp or extinguish the light and a special feature of the preferred form is that movement of the lamp to operate the switch is always toward the socket, that is, pushing the unlighted lamp will light it and pushing the lighted lamp will extinguish the light.

Other features of my invention will be pointed out below.

In the accompanying drawings: Figure 1 is a central longitudinal sectional view of a device embodying the preferred form of my invention; Fig. 2 is a section on line 2—2 of Fig. 1; Figs. 3 and 4 are details of the switch mechanism forming part of the device shown in Fig. 1; Fig. 5 is a central longitudinally sectional view of another form of the invention; Fig. 6 is a similar view of a third form of the invention; Fig. 7 is a view like Fig. 6 but showing the parts in differ-

ent positions; Fig. 8 is an elevation of the two porcelain blocks of the device shown in Fig. 7 showing the parts mounted on said blocks; Fig. 9 is an elevation of the stationary porcelain block hereinafter described; Fig. 10 is a plan view of a porcelain block shown in Fig. 9; Fig. 11 is a section on line 11—11 of Fig. 7; Fig. 12 is a section on line 12—12 of Fig. 7; Fig. 13 is an elevation of the inner face of one of the two counterpart porcelain block sections which form the porcelain block shown in Fig. 9; Fig. 14 shows the device of Fig. 1 coupled to an attachment plug; Fig. 15 is a central longitudinal sectional view of a device embodying a fourth form of my invention; Fig. 16 is a section on line 16—16 of Fig. 15; Fig. 17 is a section on line 17—17 of Fig. 15; Fig. 18 is a section on line 18—18 of Fig. 15; Fig. 19 is a detail showing part of the switch mechanism of the device of Fig. 15; Fig. 20 shows my device used as a lamp socket and provided with a cord attachment through which the lamp is manipulated to operate the switch of the device; Fig. 21 is a plan view of an attachment particularly designed for use with the forms of my invention shown in Figs. 5 and 6; and Fig. 22 shows the attachment of Fig. 21 applied to the lamp of one of my devices which may be constructed like that shown in Fig. 5 or Fig. 6; Fig. 23 shows another modification.

Having reference particularly to Figs. 1 to 4 inclusive, 1 represents a porcelain block formed with a central vertical hole 2 which at its lower end connects with a recess 3 provided at the lower end of block 1. Within the hole 2 is a bushing 4 provided at its lower end with a flange or head and having its upper end threaded to receive upon it a nut 5 by means of which the bushing is securely held within the block 1. Rotatably mounted upon the lower end of bushing 4 is a movable contact 6, Fig. 4, provided with downwardly projecting ratchet teeth 7 to cooperate with upwardly projecting ratchet teeth 8 provided on a disk 9 mounted upon a screw stem 10. Disk 9 is made upon its inner periphery with a lug 11 occupying a spiral groove 12 provided on the exterior of stem 10, and is yieldingly held against movable contact member 6 by a spring 13. Stem 10 near its lower end is provided with a head 14 and has its extremity threaded to receive upon it an interiorly threaded center contact 15 by means of which the lower end of the stem is rigidly fastened to a movable porcelain block 16. To the underside of the movable porcelain block 16 is secured by means of bolt 17 a screw threaded shell 18 adapted to receive the block of an electric lamp, attachment plug or other electric fixture or appliance. The contact member 6 is provided with two diametrically opposite wings 19 and 20 which coöperate with a sta-

tionary contact member 21 fastened to the porcelain block 1 and adapted to be connected through binding post 24 with one of the line wires 25 of the circuit. The other line wire 26 of the circuit is connected with a binding post 27 which is electrically connected with a spring contact finger 22 mounted on porcelain block 1 and engaging a metal contact member 23 fastened by means of one of the bolts 17 to the movable porcelain block 16. The bolt 17 which holds contact member 23 in place electrically connects the contact member with the threaded shell 18. When the circuit is closed through my improved switch device it extends from one line wire to the stationary contact 21 thence through the movable contact member 6 to stem 10 which leads to the center contact 15. From the center contact 15 the circuit passes through the lamp or other instrument connected with the shell 18, back to said shell and thence through bolt 17 to contact member 23 from whence it passes through contact finger 22 which is connected with the other line wire. By referring to Fig. 1 it will be seen that the contact member 6 is electrically connected with stem 10 not only through the bushing 4 but also through the toothed washer 9 which amply provides for the passage of the current. The exterior of the stem 10 is made with a longitudinal key-way 28 into which projects a lug 29 from sleeve 4 which serves by its engagement with said key-way to lock said stem against rotating within said sleeve, the sleeve being rigidly clamped against rotating by means of the nut 5. The wings 19 and 20 of movable contact member 6 also coöperate with a pair of spring jaws 30 and 31 secured to block 1 in the path of said wings and located ninety degrees away from the stationary contact 21. These spring jaws 30 and 31 form no part of the circuit. When the screw shell 18, block 16 and stem 10 are shoved upwardly the spiral groove 12 acts upon lug 11 to rotate disk 9 whose teeth engaging with the teeth on contact member 6 act to move said contact member with said stem. The limit of inward movement of screw shell 18, block 16 and stem 10 is arranged so that when block 16 is brought up against block 1 the spiral groove 12 has rotated disk 9 and contact member 6 to the extent of ninety degrees. If at the start of this inward movement of the screw shell 18 and parts carried thereby, the wing 19 of contact member 6 is in position between the jaws of the stationary contact 21, then at the completion of the inward movement of screw shell 18 said wing will have been shifted from the stationary contact member 21 into a position between the two spring jaws 30 and 31 which serve by frictional engagement with said wing to hold the contact member 6 against returning, or reverse

movement, when screw shell 18 and the parts carried thereby are forced outwardly to their normal positions by the spring 13. The outward movement of the screw shell 18 and the parts carried thereby is limited by the engagement of the lug 29 with the end of the key-way 28.

When my improved switch device is used with a lamp and it is desired to light the lamp, this may be accomplished as illustrated by merely pressing inward upon the bulb 32 of the lamp. The pressure on the lamp forces the screw shell 18 and parts carried thereby inward and shifts contact member 6 ninety degrees as described carrying one of its wings into engagement with the stationary contact 21 and thereby closing the circuit through the filament 33 of the lamp. When it is desired to extinguish the light the bulb 32 is again pressed upon which results in contact member 6 being moved again to the extent of ninety degrees carrying said wing out of engagement with the stationary contact 21 and opening the circuit of the lamp.

In the form of Fig. 1 it may be preferable to use a lamp having a considerable neck but if it is desired to use the form of lamp in which the bulb flares directly from the threaded metal portion I may flare the insulating lining 34 and the shell 35 at their lower edges to accommodate the shape of the last mentioned type of lamp.

As will be observed the construction described provides a keyless switch device for use with a lamp or attachment plug or other electric fixture or device.

In the form of my invention shown in Fig. 5 the screw shell 18 is secured to the under-side of a porcelain block 16^a provided with a center contact 15 screwed onto the lower threaded extremity of a post 10^a which is thus rigidly connected with said porcelain block by the center contact. The post 10^a extends upwardly through the porcelain block 1^a which for construction reasons may be made in two pieces fastened together by screws 37. Near its upper end post 10^a is made with a beveled enlargement 38 co-operating with a pair of springs 39 pocketed within recesses 40 within the block 1^a. The post 10^a carries a spring contact 41 which cooperates with a contact 42 fastened by means of a bolt 43 to the porcelain block 1^a, said bolt serving also as the binding post for one of the line wires 44. The other line wire 45 is connected with a binding post 46 forming part of a fixed contact member 47 mounted within block 1^a. The lower end of the fixed contact member 47 extends below porcelain block 1^a and into a notch 48 formed in the porcelain block 16^a where it is provided with an enlargement or head 49. The head 49 cooperates with a pair of spring jaws or contacts 50 riveted or otherwise secured to and

in electrical contact with the screw threaded shell 18. Normally the porcelain block 16^a will occupy the position shown in Fig. 5 with the contacts 41 and 42 separated and the contacts 47 and 50 separated, said block 70 being held in this position by the engagement of the springs 39 with the underside of the beveled enlargement 38. When it is desired to close the circuit through this switch device the lamp, attachment plug or other device connected with the screw shell 18 is pulled downwardly until the largest part of the beveled enlargement 38 passes the angular portions of the springs 39 whereupon said springs act upon the upper beveled side of the enlargement 38 to accelerate the downward movement of post 10^a and parts connected therewith, thus producing a "quick make" between contacts 41 and 42 and contacts 47 and 50 and this by a longitudinal movement of the bridging member. When post 10^a is thus forced downwardly by the springs 39 the shoulder 51 immediately under the enlargement 38 engages the bottom 52 of recess 40 which serves as a stop to limit the downward movement of post 10^a. When it is desired to open the circuit of the lamp, attachment plug or other device connected with the screw shell 18, said device is shoved inwardly carrying with it the screw shell 18, block 16^a and post 10^a. As the largest part of the enlargement passes the angular ends of the springs 39 the latter act upon the lower beveled side of said enlargement to accelerate the upward movement of post 10^a and parts connected therewith thereby producing a "quick break" at the contacts 41 and 42 and contacts 47 and 50. When the post 10^a occupies either of its two positions it is yieldingly held there by the engagement of the springs 39 with the beveled enlargement 38. As will be observed in this second form of my invention the screw shell 18 may be shifted from closed position to open position or vice versa and when so shifted the springs 39 serve to hold it against return movement. In this form of my invention the porcelain block 16^a and screw shell 18, like corresponding parts 16 and 18 in Fig. 1, constitute the supporting member for the supported member which may be a lamp, attachment plug or other device.

The device of Fig. 5 when used with a lamp is operated to close the circuit through the lamp by pulling down upon the latter and being shifted in the reverse direction to extinguish the light or open the circuit through the lamp.

In both forms of my invention so far described as well as in those forms presently to be described the insulating lining 34 and shell 35 are without perforations for laterally projecting actuators for the reason just given, namely, that I do not use laterally

projecting actuators which require perforation of the insulating lining and of the outer shell.

In the form of my invention shown in Figs. 6 to 13 inclusive the stationary porcelain block is made up of two counterpart pieces of porcelain 1^b, Fig. 13, and is provided with a contact finger 22^a like the contact 22 of Fig. 1, which coöperates with a spring contact finger 23^a like the spring contact finger 23 of Fig. 1. The two pieces of porcelain 1^b which make up the stationary porcelain block are provided upon their inner faces with registering recesses 40 within which the springs 39 are pocketed. Also in this form of my invention the movable porcelain block 16 has the screw shell 18 fastened to it by means of bolts 17 and the center contact 15 is screwed onto the lower end of a post 10^b so as to fasten said post to said block as in Fig. 1. The two pieces of porcelain 1^b are made upon their inner faces with registering recesses 53 which pocket and support a metal contact ring 54 that is provided with two downwardly extending flexible contact fingers 55 coöperating with an enlargement 6^a provided on the post 10^b. The contact ring 54 is made with an extension 56 that is fastened to the porcelain block 1^b by means of a bolt 57 which serves also to hold the two parts of the porcelain block together and has a binding post for a line wire 58. The other line wire 59 is connected with another binding post bolt 60 which fastens the contact member 22^a to the stationary porcelain block and serves also to hold the two sections of said block together. This form of my invention is operated like the form shown in Fig. 5, the contacts 22^a and 23^a being permanently in engagement and the circuit is opened and closed merely by moving the enlargement 6^a into and out of engagement with the contact fingers 55, through in and out movement of the screw shell 18 and post 10^b. In this form of my invention the enlargement 38 on post 10^b acts to provide a "quick make and quick break" between the enlargement 6^a and contact fingers 55 by an endwise or longitudinal movement of the post 10^b and screw shell 18.

In the form of my invention shown in Figs. 15 to 19 inclusive 1^c indicates the stationary porcelain block, 16^b the movable porcelain block, 18 the screw shell, 34 the lining of insulating material inclosing said parts, 35 the metal shell surrounding the lining 34, 36 the cap of shell 35 and 25 and 26 the line wires. The stationary porcelain block 1^c is made with a recess 61 within which is arranged a ratchet wheel 62 provided upon one face with a series of studs 63 coöperating with a spring pawl 64 fastened by a screw 65 to the movable porcelain block 16^b. The porcelain block 16^b is

moved toward and from the stationary porcelain block 1^c to open and close the circuit as before and as the spring pawl 64 moves with it it acts to rotate ratchet wheel 62 step by step. The ratchet wheel 62 is made with four laterally projecting lugs 66 adapted by the rotation of said wheel to be brought successively into engagement with a stationary contact 67 fastened by a screw 68 to the stationary porcelain block 1^c. The contact 67 is made with a downwardly extending finger 69 which is in permanent engagement with a contact finger 70 riveted or otherwise secured to the screw shell 18. A spring detent 71 bears against ratchet wheel 62 and coöperates with the studs 63 to prevent reverse movement of said ratchet wheel on the down strokes of pawl 64. This detent 71 is fastened to the stationary porcelain block 1^c by means of a screw 72 which serves also as a binding post with which the line wire 25 is connected. Detent 71 not only prevents reverse movement of ratchet wheel 62 but also serves as an electric connection between binding post screw 72 and said ratchet wheel. The studs 63 are provided and arranged so that each upward movement of pawl 64 rotates ratchet wheel 62 a distance equal to the angular distance between two of the studs so that every other up stroke of pawl 64 shifts one of the lugs 66 into engagement with contact 67 while the alternate up strokes of the pawl 64 disconnect ratchet wheel 62 and contact 67. The center contact 15^a is made with a threaded hole to receive the lower threaded extremity of a post 10^c provided at its upper end with a head 73 beneath which is arranged a spring 74, said spring serving to normally hold the block 16^b against the porcelain block 1^c. On its under side the porcelain block 1^c is made with a recess 75 within which is arranged a contact 76 that is fastened to the porcelain block 1^c by means of a screw 77. The screw 77 serves as a binding post to which the other line wire 26 is connected, and the contact 76 is in permanent engagement with a stationary contact 78 provided on the center contact 15^a. The screw shell 18 and porcelain block 16^b are moved bodily toward and from the porcelain block 1^c to open and close the circuit at 71—67 and when thus moved the contacts 78 and 70 slide upon the contacts 69 and 75 without leaving the latter. In Fig. 15 I have shown a connecting plug 79 mounted within the screw shell 18 and at 80 and 81 are the line wires leading from this connecting plug to the heater or other instrument. When the circuit through the heater or other instrument connected with the wires 80 and 81 is open and it is desired to close the same the operator may accomplish this merely by pulling upon said wires and then releasing them. The pull upon the wires 130

draws the connecting plug 79, screw shell 18, porcelain block 16^b and post 10^c outwardly against the pressure of spring 74 which latter returns said parts to their innermost positions when the pull upon wires 80 and 81 is relaxed. Pawl 64 moves with the porcelain block 16^b and through its engagement with the ratchet wheel 62 turns the latter one step carrying one of the lugs 66 into engagement with the contact 67 thereby closing the circuit through the heater or other instrument. When it is desired to open the circuit through the heater or other instrument the operator will again pull upon the wires 80 and 81 which results in another in and out movement of the connecting plug 79 and parts connected therewith. When block 16^b is thus moved with the connecting plug 79 its pawl 64 again moves ratchet wheel 62 one step carrying the lug 66 resting against contact 67 away from and out of engagement with the latter thus opening the circuit through the heater or other instrument. It will thus be seen that with this form of my invention an important advantage resides in the construction which permits of its being operated from a distant point to open and close the circuit through the medium of the wires 80 and 81.

When my improved switch device is used to hold a lamp and is to be placed in an elevated position where it cannot be conveniently reached I may provide an attachment 94^a shown in Fig. 20 consisting of an annular flexible strap 95^a whose ends are fastened together by means of a screw 82 so that the strap is confined between two shoulders 83 and 84 that are provided upon the exterior of shell 35. This strap 95^a is made with a depending arm 85 extending downwardly alongside of the lamp bulb 32 and at the lower end of this arm there is provided a bell-shaped cord guiding aperture 86. One end of a cord 87 is tied around the shank of the bulb 32 and said cord extends therefrom downwardly through the guide 86 with its lower end arranged in a convenient position. This attachment is applicable to the switch device shown in Fig. 15.

When my improved switch device is used to hold a lamp and is arranged in a more or less elevated position with the lamp uppermost as shown in Fig. 22 I prefer to provide the lamp with the attachment shown in Figs. 21 and 22. This attachment comprises two metal strips one of which 88 is bent near its middle to form a loop 89 adapted to extend half way around the shank of the bulb 32 with the ends 90 of said part bent upwardly and outwardly and having their extremities hooked as at 91. The other part of this attachment comprises a metal strip 92 bent to form a loop to extend around the

other half of the bulb and having its extremities fastened to the part 88 by means of two screws 93. This form of attachment may be used with any one of the switch devices herein shown and by grasping either or both of the arms 90 the operator may conveniently move the lamp to operate the switch device.

The stationary porcelain block 1^c of Fig. 15 is made at its lower end with two diametrically opposite lugs 94 occupying two notches 95 provided in the movable porcelain block 16^b. These lugs and sockets connect the two porcelain blocks so that they can be moved relatively toward and from each other but are held against relative rotative movement.

In Fig. 23 I have shown my invention embodied in a switch connector or union adapted to be used for instance, to connect an ordinary lamp or cord plug with an ordinary socket. This form of my invention comprises a screw shell 18 secured to a movable porcelain block 16 carrying a spring contact finger 23^a coöperating with a contact 22^b. The block 16 carries a center contact 15 which fastens a stem 10^b thereto, said stem, like the stem 10^b of Fig. 6, coöperating with a pair of contact fingers 55 projecting from a metal ring 54. The ring 54 is made with an extension 96 provided near its extremity with a threaded hole into which is screwed the threaded end of the shank of another center contact 97. The stem 10^b is, like the stem 10^b of Fig. 6, made with an enlargement 38 coöperating with a pair of springs 39 pocketed within a stationary porcelain body 97^a. At its lower end the body 97^a is made with a skirt 98 inclosing screw shell 18, and at its upper end with a plug 99 upon the outside of which is arranged a second screw shell 100. This screw shell 100 is held in place on plug 99 by lugs 101 which are bent inwardly into recesses 102, and carries the contact 22^b which may be integral therewith or soldered thereto. The porcelain body 97^a may be made in two counterpart sections fastened together by bolts 103. The shell 100 and center contact 97 constitute engaging means provided upon this form to attach to the terminals in the mouth of an ordinary socket.

Although an attachment plug is shown in Fig. 15 yet a lamp might be used because of the form of shell and it is to be noted that I do not limit myself to any particular form of shell.

I do not claim in this application the subject matter of the combination involving outward movement to make the circuit or the combination involving outward movement to break the circuit or the handle for moving the lamp support or the combination of an electric socket for a switch mechanism with longitudinally moving means

for operating the same and engaging means to attach to the terminals in the mouth of another socket as I intend to make those features the subject of another application 5 or applications.

What I claim is:

1. A device of the character described comprising switch mechanism including an immovable contact and a contact movable 10 into and out of engagement with said immovable contact; a support movable longitudinally to operate the switch mechanism, and an electrical appliance carried by the support and having a terminal in circuit 15 with said switch mechanism.
2. A switching device comprising a receptacle; switch mechanism carried by the receptacle; and a support mounted on the receptacle and movable longitudinally and inwardly both to make and break the circuit through said switch mechanism and being in circuit with said switch mechanism; and automatic means to return said support to its outermost position after each operation. 20
3. A device of the character described comprising a socket; switch mechanism mounted in said socket; a lamp having terminals electrically connected to said switch mechanism; a supporting member carrying 25 said lamp and mounted on said socket and movable inwardly to operate said mechanism to make the circuit and light said lamp and also movable inwardly to operate said mechanism to break the circuit and extinguish the light in said lamp; and automatic means to move said member to its outermost position after each operation. 30
4. A device of the character described comprising a socket; a body of insulating 40 material mounted in said socket; switch mechanism on said body including a contact; a rotary member having wings to engage said contact and having projecting teeth; another rotary member having projecting teeth to engage the teeth on the winged member and having also a central bore with an internally projecting lug; and
5. A switching device comprising switch 50 mechanism; and a supporting member movable longitudinally and inwardly both to make and break the circuit through said switch mechanism and having a portion in circuit with said switch mechanism; and automatic means to return said member to its outermost position after each operation. 55
6. A device of the character described comprising a socket; switch mechanism including an immovable contact and a movable contact; a lamp having terminals in circuit with said switch mechanism and a rigid support for said lamp movable longitudinally by the user to move said movable contact into and out of engagement with 60 said immovable contact. 65
7. An electric light socket comprising switch mechanism; a lamp having a terminal in circuit with said switch mechanism; and a support for said lamp movable longitudinally and inwardly to make and also to break the circuit; and automatic means to return the support to its outermost position 70 after each operation. 75
8. An electric light socket comprising switch mechanism including an immovable contact and a contact movable into and out of engagement with said immovable contact; a support movable longitudinally to operate the switch mechanism and having a 80 terminal in circuit with said switch mechanism; and a lamp carried by said support and having a terminal in contact with the terminal of said support. 85
